UNITED STATES PATENT OFFICE.

BENJAMIN ANDREWS, OF HOUSTON, TEXAS, AND WILLARD C. AVERILL, JR., OF MERAUX, LOUISIANA.

PROCESS OF TREATING HYDROCARBONS.

1,329,739.

Specification of Letters Patent.

Patented Feb. 3, 1920.

Application filed September 19, 1918. Serial No. 254,737.

To all whom it may concern:

Be it known that we, BENJAMIN ANDREWS, residing at Houston, in the county of Harris and State of Texas, and WILLARD C. AVERILL, Jr., residing at Meraux, in the parish of St. Bernard and State of Louisiana, both citizens of the United States, have invented or discovered certain new and useful Improvements in Processes for Treating Hydrocarbons, of which the following is a full, clear, and complete disclosure.

Our invention relates to a process for treating comparatively heavy petroleum and other hydrocarbon oils and their distillates and derivatives, in order to produce from such heavy oils a large yield of gasolene or other light, easily volatile liquids.

One object of our invention is to provide a process of the kind described, which will be safe and efficient, and by the use of which large yields of gasolene and light hydrocarbon liquids may be obtained from heavy oils, and which will be free from trouble arising from the accumulation of carbon. Other objects and advantages of our invention will be obvious from the following specification.

In practising our improved process, we cause heavy hydrocarbon oil, or the vapors thereof, to be heated and converted into lighter liquids by passing it through tubes containing a heated liquid of such a character that it will not distil or vaporize at the temperature required for converting the oil. The arrangement employed is such that the liquid in the tubes is mixed with the oil vapors, and is rapidly circulated through the tubes. When operating in this way, we find that the tubes may be comparatively short; that large quantities of oil may be passed through them, and that large yields of gasolene may be obtained from heavy oils that would yield practically no gasolene if subjected to a straight distillation process; moreover, we find that the presence of the liquid in the tubes, particularly when kept in rapid circulation, effectively prevents the accumulation of carbon, so that after extensive runs the tubes remain practically clean.

Our process may be carried out at atmospheric pressure, but we prefer to maintain the heated liquid in the tubes under a uniform pressure, higher than atmospheric pressure. This super-atmospheric pressure may be obtained by restricting and regulating the escape of the hydrocarbon vapors;

but preferably, and more conveniently, by subjecting the apparatus, including the liquid in the tubes, to the pressure of steam admitted and maintained at a uniform pressure. The vapors on leaving the tubes may be condensed and separated in any well-known way; but we prefer to conduct them first to a dephlegmator or separating tank, where the heavy oils may be condensed and separated out, and then to a condenser maintained at a comparatively low temperature but also preferably maintained under pressure, in which condenser the light oils are condensed and drawn off.

In the drawing accompanying and forming a part of this specification, we have illustrated one form or embodiment of apparatus suitable for use in practising our process, which will be readily understood from a description of this apparatus and its mode of operation.

In the drawing Figure 1 is a vertical section of the complete installation; Fig. 2 is a side elevation, partly in section, of the furnace, including the tubes containing the heated liquid and through which the hydrocarbon is to be passed; Fig. 3 is a detail section view of two of the tubes.

Referring in detail to the drawing, we have shown at 1 a furnace which may be of any conventional type. This furnace supports a header 2, to the lower side of which there are secured a plurality of U-shaped tubes 3. The ends of these U-shaped tubes open into the header 2, and the body of the tubes extends from the header down into the furnace, so as to be heated. An oil supply pipe 4 is disposed in one leg of each of the U-shaped tubes, and these pipes 4 are all connected with a common oil supply header or pipe 5, so that by opening the cocks 6 and 6^a, the oil to be treated may be caused to flow down the tubes 4 and into the heated liquid in the pipes 3. The pipes 3 are filled with a heated liquid such as melted lead, which will not distil at the temperature employed, and this heated liquid extends up into the header, with its surface at the level indicated by the broken line *a*, Fig. 1. 7 designates a dephlegmator or air-cooled condenser, and this is filled with broken pottery or other material adapted to expose a large surface to the vapors. This dephlegmator is connected with the header 2 by the pipe 8, and also through the

pipe 9 with the water-cooled condenser 10. 11 designates a tank adapted to receive the light liquids condensed in the condenser 10. Any fixed gases passing into this tank 11 5 may be permitted to escape through the pipe 12, and the light hydrocarbons may be drawn off through the pipe 12. When it is desired to operate the apparatus under a uniform pressure, this may conveniently be done by 10 admitting steam into the dephlegmator through the pipe 14 and valve 30, which is preferably a pressure regulating valve adapted to admit steam at the pressure desired.

In practising our improved process in the 15 apparatus described, we proceed as follows:

The heavy hydrocarbon oil is supplied to the header 5 under pressure, and flows from this header down through the small pipes 4 into the melted metal in the tubes 3. This 20 metal is maintained at a temperature suitable for converting the oil, and this will vary with the character of the oil treated. When treating a distillate of 32 degrees Bé., we have found a temperature of 500 degrees C. 25 and a pressure of 75 pounds to give good results. It is to be understood, however, that both the pressure and temperature may, and should be varied, in order to get the best results. An operator, by noting the results 30 had with the particular oil treated, can readily determine the most advantageous values for temperature and pressure. We preferably provide a thermometer 35 disposed in the liquid in the header, and also 35 a thermometer 37 disposed in the vapors in the header, whereby temperature observations may be made. The melted metal in the tubes is kept in rapid circulation by the liquid, which immediately vaporizes on coming 40 in contact with the metal and rises in the form of bubbles, as indicated in Fig. 3. This causes the lead to rise in one leg of the tube and to descend in the other, as indicated by the arrows. The vapors pass 45 through the header 2 to the dephlegmator, as above explained, and the heavy oils, along with any water of condensation accumulating in this device, may be drawn off from time to time through the outlet 17. The 50 lighter vapors pass through the dephlegmator 7 into the water-cooled condenser 10 and are condensed in tank 11, as above explained. The steam admitted through the pipe 14 and reducing valve 30, with co- 55 operation of a pressure relief and regulating valve 15, which is set so as to throttle the escaping mixture, operates to maintain a uniform pressure throughout the apparatus.

In actual operation the only appreciable 60 accumulation of carbon noted, is on the surface of the melted lead in the header 2, and this may be easily removed by shutting off the oil supply and opening the cock 40 and admitting live steam through cock 41 so as 65 to blow out the carbon.

The apparatus described herein is described and claimed in our pending application Serial No. 147,780, filed February 10, 1917.

While we have disclosed only the preferred method of practising our improved process, we are aware that modifications may be made therein without departing from the scope of our claims.

What we claim is:

1. The method of treating hydrocarbon oil, which consists in injecting the oil into tubes containing a melted metal, circulating the resulting vapors and melted metal through said tubes, and then withdrawing 80 the hydrocarbon vapors.

2. The method of treating hydrocarbon oil, which consists in injecting the oil into tubes containing a melted metal maintained under a pressure greater than atmospheric 85 pressure, circulating the resulting vapors and melted metal together in the same direction through said tubes, and withdrawing the hydrocarbon vapors.

3. The method of treating hydrocarbons 90 by injecting same into a molten metal confined in a tubular circulatory heating system in such manner as to cause intimate contact between the metal and hydrocarbons and circulation of the metal, the vapors and 95 metal moving together in the same direction and withdrawing the hydrocarbons.

4. The method of treating hydrocarbons by injecting same in such manner into a molten metal confined in a tubular circulatory heating system kept under a super-atmospheric pressure as to cause intimate contact 100 between the metal and hydrocarbons and rapid circulation of the metal and hydrocarbons together in the same direction 105 within the tubular heating system and condensing the resultant vapors.

5. The method of treating hydrocarbons by injecting same into a molten metal confined in a tubular circulatory heating system in such manner as to cause intimate contact between metal and hydrocarbons and rapid circulation of the metal and vapors together in the same direction and condensing the resultant vapors under super- 115 atmospheric pressure.

6. The method of treating hydrocarbons by injecting same into a molten metal confined in a tubular circulatory heating system in such a manner as to cause rapid circulation of the metal through the heating system, the vapors moving in the same direction as the metal and in contact therewith, and then withdrawing the hydrocarbons, the system throughout the process being subjected to steam pressure.

7. The method of treating hydrocarbon by injecting same into a molten metal confined in a tubular circulatory heating system in such manner as to cause intimate contact be- 130

tween the metal and hydrocarbons and the circulation of the metal and the hydrocarbons continuously in one direction, and then withdrawing the hydrocarbon.

- 5 8. The method of treating hydrocarbons comprising injecting oil into one of two tubes containing melted metal and connected at top and bottom, whereby the density of the liquid in one tube is decreased and
- 10 an upward current of mingled metal and hydrocarbon is produced in the tube into which the oil is injected, and a downward flow of metal occurring in the tube connected thereto.
- 15 9. The method of treating hydrocarbons comprising injecting oil into one of two tubes containing melted metal and connected at top and bottom at a point sufficiently

below the surface of the melted metal to produce an upward motion of the mixed 20 metal and vapors which is rapid as compared with a non-directed current of the same materials.

10. The method of treating hydrocarbons comprising injecting oil into one of two 25 tubes containing melted metal and connected at top and bottom at a point sufficiently below the surface of the melted metal to produce an upward motion of the mixed metal and vapors which is rapid as com- 30 pared with a non-directed current of the same materials, and maintaining super-atmospheric pressure at the surface of said melted metal.

BENJAMIN ANDREWS.
WILLARD C. AVERILL, JR.
